UNITED STATES PATENT OFFICE.

HENRY B. PITNER, OF AURORA, ILLINOIS, ASSIGNOR TO ALFRED FRESCHL,
OF MILWAUKEE, WISCONSIN.

MEANS FOR MAKING PLAITED WORK IN UPHOLSTERING.

SPECIFICATION forming part of Letters Patent No. 577,809, dated February 23, 1897.

Application filed February 23, 1895. Serial No. 539,460. (No model.)

To all whom it may concern:

Be it known that I, HENRY B. PITNER, a citizen of the United States, residing at Aurora, in the county of Kane and State of Illinois, have invented certain new and useful Improvements in Means for Making Plaited Work in Upholstering; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention has reference to improvements in means for making plaited work in upholstering; and it consists in the mechanism hereinafter described for receiving the outer or upper fabric, folding the same in 20 plaits, retaining the same in place, holding the filling, pressing the latter into suitable form, and placing the tuft-buttons at certain predetermined locations in the completed work. I attain the above purposes by the 25 mechanism illustrated in the accompanying drawings, in which—

Figure 1 is a perspective view of an upholstering-machine embodying my invention. Fig. 2 is a perspective view of the bottom or 30 base of the mold, the upwardly-projecting side and end pieces being removed. Fig. 3 is a perspective view of the clench-iron. Fig. 4 is a perspective view of one of the plaiters on an enlarged scale. Fig. 5 is a perspective 35 view of the pin-board. Fig. 6 is a perspective view of the follower-board. Fig. 7 is a perspective view of the pressure-head and its end pieces. Fig. 8 is a sectional elevation of the upholstering-machine. Fig. 9 is a vertical section, on an enlarged scale, of the mold, composed of the bottom and the upwardly-projecting side and end pieces, the sectional plane following the line 9 9 in Fig. 2.

Similar letters and figures refer to similar 45 parts throughout the several views.

My improved machine is intended to be of such size as to form and complete at one operation the plaited upholstering required for carriage, sofa, or other padded backs or cushions of any desired size; but as the parts are the same in kind in every instance I shall in this application merely show and describe my

invention as employed in the seating of two tuft-buttons, or the construction of six biscuits.

55

A is a portable frame consisting of the base 1, two standards 2, and the upper cross-beam 3, seated at its extremities in and supported by said standards 2.

B is a bench permanently seated on the 60 base 1, a short distance within standards 2, and suitably supported by legs 4 over the center of base 1.

C is the mold for receiving, in an inverted position, the fabric which constitutes the upper or, in case the plaiting is used in a vertical position, the outer fabric. On the outer edge of the walls of said mold are formed the plait-receiving recesses P, opposite the lines of plaiting. In the base of the mold are formed 70 openings 5 at the intended localities for the tuft-buttons, and on the inner surface of the bottom of mold C there are seated the hollow tuft-opening guards D. Said guards D are of a tubular character, are of a height about 75 that of the filling when the latter is compressed, and have each four equidistant, longitudinal flutes 6 in their periphery and may be constructed of more or less of said flutes. The purpose of the guards D is to prevent 80 the filling from working into the openings 5 left for the insertion of the tuft-buttons and to fold the cloth equally to form the plaits.

The inner surface of the bottom of the mold C is provided with the concavities 7, of about 85 the form and size of the upper surface of the finished biscuits.

The mold C in use is placed upon the table B, being held firmly thereon by short dowel-pins 7', seated on the table B, which enter 90 small openings 8 in the base of mold C, as shown in Figs. 8 and 9. The fabric for the upper or outer side of the filling is then laid face down in the mold C and by means of plaiters E, Fig. 4, is properly plaited and 95 forced to the bottom of the guards D and mold C. The plaits on the outer rows are laid by hand and temporarily tacked in the recesses P on the outside of the mold. The lower portion of each plaiter E is recessed so 100 as to straddle one of the upwardly-projecting tucking guards, tubes, or devices D. When the guards are provided with four equidistant flutes, as shown, each plaiter E is recessed

so as to have its lower portion composed of four equidistant points 10, which are so far apart that in applying the plaiter to the guard the four points pass down in the flutes on the 5 outer side of the guard. After the fabric or other covering has been spread over the guards D the plaiters are applied to the same and remain in place until the filling has been applied. The plaiters press the fabric closely 10 down around the guards, drawing the fullness of the fabric into equidistant plaits which radiate from the guards. After the fabric has been so plaited and while it is held in position by the plaiters the filling is applied. The guide-box F, which is essentially 15 a box without either top or bottom, is then placed over the mold C, with its lower edge about on the plane of the table B, and is temporarily suspended by its frictional contact 20 with the rubber or leather buffers 9, formed on the outside of mold C. The follow-board G is then placed on the filling and pressed down by hand, and the plaiters E are then withdrawn, the follow-board G removed, and 25 the usual strawboard H is then placed on top of the guide-box F, and the clench-iron J is put on top of said strawboard. The strawboard and clench-irons are held in place by short pins 11, seated in the upper edge of 30 guide-box F. The follow-board G is then placed on top of the clench-iron, and the pressure-head K, consisting of the main center 12 and end cross plates 13, is then placed on the upper surface of the follow-board G and held in position by suitable pins 14, seated 35 in the upper surface of said follow-board. Downward pressure is then exerted on the beam K and the filling within the guide-box F by means of a descending screw L, seated 40 centrally in the upper cross-beam 3 and working in a fixed threaded nut 15, attached to the lower side of said beam. After the filling within the guide-box F is thus downwardly compressed within the mold C the 45 guide-box F is dropped below the bench B and suitable clamps caused to grasp vertically the follow-board and the bottom of the mold C at the sides of the latter. Lateral recesses 16 are formed centrally in the sides of 50 the bench B to admit said clamps. The screw L is then withdrawn, the pressure being removed, and the follow-board G, mold C, and interposed filling, strawboard, and clench-iron clamped together as aforesaid, taken to the 55 work-bench, the temporary tacks removed, and the fabric and strawboard tacked together or sewed around the edges; or, if tacks are used, they are driven from the fabric side toward the clench-iron and clenched 60 by meeting the latter. If tacks are not intended to be used on the edges of the plaited work, the clench-iron may be omitted. The tuft-buttons or clench-nails are then inserted in the openings 5 in the bottom of the mold 65 C and are forced through the guards D and the strawboard H by means of the pins 17 of the pin-board M and are held in position

thereby, projecting through the strawboard H at the large openings 18 in the follow-board G, and are there clenched by any suitable instrument, the tuft-buttons being held meanwhile from withdrawal by the work resting on the pin-board M, the pins 17 thereof pressing upward and against the heads of the tuft-buttons while the latter are being 75 clenched on the upper surface of the strawboard H in said openings 18. I usually make the guide-box F eight and one-half inches deep, but it may be made less or more, according to the thickness of the work desired. 80

What I claim as my invention, and desire to secure by Letters Patent of the United States, is—

1. In a machine for making plaited work in upholstering, the combination of a frame 85 A provided with base 1, standards 2, beam 3 and nut 15, the bench B seated centrally on the base of said frame, moldboard C seated on said bench, and provided with tuft-hole guards D, having fluted sides 6, plaiters E 90 adapted to be pressed downward on said flutes 6 and to project upwardly from the guards D, guide-box F adapted to inclose mold C and to project upwardly therefrom, and adapted to receive and retain, during pressure, the 95 necessary filling, strawboard H placed over said filling, and follow-board G imposed upon said strawboard, and the screw-bolt L seated in nut 15 and adapted to exert downward pressure immediately or immediately upon said 100 follow-board and thereby force said filling within said mold substantially as shown and for the purpose described.

2. In a machine for making plaiting in upholstering, a suitably-supported mold C, provided with upwardly-projecting tuft-hole guards D, having fluted sides 6, plaiters E adapted to force the fabric down over guards D, and form radial plaits in right lines therefrom, guide-box F adapted to inclose mold C 105 and extend upwardly therefrom to receive the necessary filling, strawboard H, placed over such filling, and means substantially as shown for compressing the latter within the mold C, and suitable means for seating and 110 clenching or otherwise fastening the tuft-buttons within the guards D for the purpose specified.

3. The combination with the mold provided with upwardly-projecting hollow tucking devices, of a follower provided with openings registering with said tucking devices, and a pin-board provided with pins adapted to be inserted from the bottom of the mold into said tucking devices and support the tuft-buttons, substantially as set forth. 120

4. The combination with the mold provided with fluted hole-guards projecting upwardly from the base of said mold, of plaiters provided with downwardly-projecting points 130 adapted to be pressed down the fluted sides of said guards and to form the fabric into plaits, substantially as set forth.

5. In an upholstering device, the combina-

tion of a base provided with upwardly-projecting tucking devices, of detachable plaiters which are adapted to straddle said tucking devices, substantially as set forth.

5 6. In an upholstering device, the combination of a base provided with upwardly-projecting tucking devices, of detachable plaiters provided at their lower ends with downwardly-projecting points which straddle said tucking devices, substantially as set forth.

10 7. In an upholstering device, the combination of a mold provided with perforated tucking devices, a surrounding casing, plaiters which straddle said tucking devices and force the material forming the outside of the article being formed over said tucking devices, a top, and means for forcing the parts together and holding them while the upholstering op-

eration is being completed, substantially as set forth.

8. In an upholstering device, the combination with the mold provided with upwardly-projecting hollow tucking devices, of a follower provided with openings registering with said tucking devices, detachable plaiters for forcing the material forming the outside of the article being formed down over said tucking devices, and a pin-board provided with pins adapted to be inserted from the bottom of the mold into said tucking devices and support the tuft-buttons.

In testimony whereof I affix my signature in presence of two witnesses.

HENRY B. PITNER.
